(57) **CLAIM**

The ornamental design for a fan blade, as shown and described.

DESCRIPTION

FIG. 1 is a perspective view of a fan blade showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

Shading is used to illustrate the curvature of the part and not color.

The claimed design is indicated by the relatively dark portions in the drawings, while the relatively light portions enclosed by broken lines are environmental and form no part of the claimed design.
